UNITED STATES PATENT OFFICE

HENRY E. ROMINE, OF SEYMOUR, INDIANA

INFANT GLIDER

Application filed November 16, 1931. Serial No. 575,455.

The present invention relates to an infant glider and has for its prime object to provide an apparatus with a seat for an infant, child or the like and means for supporting the seat so that it may be moved to and fro and retained in a level position during its movement.

Another very important object of the invention resides in the provision of an apparatus of this nature which is exceedingly simple in its construction, inexpensive to manufacture, strong and durable, easy to manipulate, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a perspective view of the apparatus embodying the features of my invention, and

Figure 2 is a front elevation thereof.

Referring to the drawings in detail it will be seen that the frame comprises four uprights 5 connected by bars 6, 6 and 7, 7 at their upper ends. A pair of spaced parallel supporting bars 8 are mounted in the frame adjacent the top thereof. Numeral 9 denotes a seat. The letters H denote a plurality of hangers. Each hanger is of substantial U-shaped formation including a cross portion 10, a pair of sides 11 and a pair of trunnions 12 extending laterally and outwardly from the upper ends of the sides 10. The trunnions 12 are journaled in suitable bearings 14 mounted in the supporting bars 8.

The cross portions 10 extend under the seat 9 in spaced parallelism and are connected to the seat by means of bearings 15. On one of the trunnions 12 there is formed a crank 16. By rocking this crank 16 it will be seen that the seat may be caused to move to and fro in a level condition so as to eliminate the danger of an infant or small child

falling therefrom as the rocking motion takes place.

It is thought that the construction, operation and advantages of this invention will now be quite apparent without a more detailed description thereof.

It is apparent that changes in the details of construction may be resorted to without departing from the spirit or scope of the invention as hereinafter claimed or sacrificing any of its advantages.

Having thus described my invention, what I claim as new is:

A device of the class described comprising four uprights, upper and lower bars connecting said uprights together, a cross beam connected to each side pair of uprights adjacent their upper ends, a plurality of U-shaped members each formed of circular stock and having the extremities of the limbs bent at right angles and journaled in the beams, one extremity and one of said U-shaped members being extended to pass through a beam and bent to form a crank handle, a seat bottom forming board seated on the bight portion of said U-shaped members with its edges spaced inwardly of the limbs of such members, and side and end boards having their lower edges connected with the upper face of said bottom board and a strip connecting the front end of the side boards together and spaced above the bottom board.

In testimony whereof I affix my signature.

HENRY E. ROMINE.
